CLOTH MATERIAL AND METHOD OF
PREPARING THE SAME

Evelyn Passavant, Los Angeles, Calif.

Application October 21, 1940, Serial No. 362,078

6 Claims. (Cl. 139—420)

My invention relates to a cloth material and method of preparing the same, more particularly to a cloth material and method of preparing the same in which bias tape is used in connection with my methods for preparing said cloth material and the objects of my invention are:

First, to provide a substantial cloth material of this class which is made of strips of prepared conventional bias tape arranged in interwoven flat connected relation;

Second, to provide a cloth material and method of preparing the same of this class in which two separate flat strips of bias tape are first sewed together along both edges thereof and then interwoven with similarly prepared bias tape strips providing an arrangement whereby opposite sides of the prepared bias tape strip may be of different colors promoting the development of various colored designs in my finished cloth material;

Third, to provide a cloth material and method of preparing the same of this class in which two conventional bias tape strips are sewed together along their opposite edges providing four thicknesses of material in each of the thus prepared cloth tape strips of my finished cloth material;

Fourth, to provide a cloth material and method of preparing the same of this class in which bias tape strips may be woven tight or loose in various portions so that the finished cloth material may take the shape of and conform to the various contours of a hat or the like;

Fifth, to provide a cloth material of this class in which eight layers of cloth goods are in superposed relation with each other providing a cloth material which is very warm to wear as clothing, strong and shape retaining when used in hats, scarfs or the like;

Sixth, to provide a novel cloth material and method of preparing the same of this class;

Seventh, to provide a novel cloth material of this class; and

Eighth, to provide a cloth material of this class which is very simple and economical of construction, efficient, durable and which will not readily wear, deteriorate or get out of order.

With these and other objects in view as will appear hereinafter, my invention consists of certain novel features of construction, combination and arrangement of parts and portions and certain methods as will be hereinafter described in detail and particularly set forth in the appended claims, reference being had to the accompanying drawing and to the characters of reference thereon which form a part of this application in which;

Figure 1 is an elevational view of some of my finished cloth material; Fig. 2 is an enlarged sectional view taken from the line 2—2 of Fig. 1 showing parts in elevation to facilitate the illustration; Fig. 3 is an enlarged fragmentary elevational view showing in detail one of the cloth strips of my cloth material formed of two pieces of conventional bias tape; and Fig. 4 is a transverse sectional view taken from the line 4—4 of Fig. 3.

Similar characters of reference refer to similar parts and portions throughout the several views of the drawing:

In the preparation of my cloth material I first 15 prepare cloth strips 1, as shown best in Fig. 3 of the drawing on an enlarged scale. Each of these cloth strips 1 is constructed of two strips of conventional bias tape. The conventional bias tape is folded inwardly at opposite edge portions 1a, as shown best in Fig. 4 of the drawing. The raw edges 1b of the conventional bias tape are positioned in opposed relation to each other at substantially the middle portion of the strips of bias tape, as shown best in Fig. 4 of the drawing. 20 The two strips of bias tape are positioned in flat engaged relation with each other having the raw edge portions 1b facing each other so that both outer sides of the prepared cloth strip 1 enclose the raw edge portions 1b of the conventional bias tape. These two strips of bias tape are sewed together near opposite edges by means of the 25 stitches 1c, as shown best in Figs. 3 and 4 of the drawing. Referring particularly to Fig. 4 of the drawing, it will be observed that the finished 30 cloth strip 1 is provided with four thicknesses of the cloth goods of the conventional bias tape. Several strips of the cloth goods are prepared as shown in Figs. 3 and 4 of the drawing and these cloth strips 1 are placed in parallel edge to edge relation to each other and are sewed together near their opposite ends by means of the 35 stitches A, as shown best in Fig. 1 of the drawing.

Other cloth strips designated 2 in Fig. 1 of the 40 drawing are prepared in identical manner with the preparation of the cloth strips 1. These cloth strips 2 are sewed together in parallel edge to edge relation at one end by stitches B and then are interwoven with the connected cloth strips 45 1 in the relation shown in Fig. 1 of the drawing. When the cloth strips 2 are completely interwoven with the cloth strips 1 in transverse relation therewith, the opposite ends of the cloth strips 2 are sewed together in parallel edge to 50 edge relation with each other by means of the 55

stitches C, as shown best in Fig. 1 of the drawing. My methods concisely for preparing my cloth material are substantially as follows:

Two strips of conventional bias tape are first secured together in the relation as shown in Fig. 4 of the drawing providing a prepared cloth strip 1, as shown in Fig. 3 of the drawing. Several of these cloth strips 1 are then secured together in parallel edge to edge relation at their opposite ends by means of stitching. Cloth strips similar and identical to the cloth strips 1 are then prepared and stitched at one end in parallel edge to edge relation with each other and are interwoven with the cloth strips 1 in transverse relation therewith. The opposite ends of these transversely disposed cloth strips are sewed together by means of stitching and my cloth material is finished.

When it is desired to have the finished cloth material of varying color combinations, the cloth strips 1 may be prepared to two different colored bias tape materials so that opposite sides of the prepared cloth strip 1 are of different colors. When the prepared cloth strips 1 are placed in parallel edge to edge relation to each other, adjacent parallel cloth strips may be of different colors promoting the development of various colored designs or patterns in my cloth material. The structural arrangement of the cloth strips 1 provides for different color combinations on opposite sides of my prepared cloth material.

Though I have shown and described a particular construction, combination and arrangement of parts and portions and particular methods, I do not wish to be limited to this particular construction, combination and arrangement, nor to the particular methods, but desire to include in the scope of my invention the construction, combination, arrangement and methods substantially as set forth in the appended claims.

Having thus described my invention, what I claim as new and desire to secure by Letters Patent is:

1. In a cloth material of the class described, the combination of interwoven cloth strips, each of said cloth strips constructed of two flat strips of conventional bias tape sewed together in flat engaged relation with each other.

2. In a cloth material of the class described, the combination of interwoven cloth strips, each of said cloth strips constructed of two flat strips of conventional bias tape sewed together in flat engaged relation with each other, each of said strips of bias tape provided with inwardly folded raw edge portions.

3. In a cloth material of the class described, the combination of interwoven cloth strips, each of said cloth strips constructed of two flat strips of conventional bias tape sewed together in flat engaged relation with each other, each of said strips of bias tape provided with inwardly folded raw edge portions, said raw edge portions in opposed relation with each other and positioned at substantially the middle portion of each of said strips of conventional bias tape.

4. In a cloth material of the class described, the combination of interwoven cloth strips, each of said cloth strips constructed of two flat strips of conventional bias tape sewed together in flat engaged relation with each other, each of said strips of bias tape provided with inwardly folded raw edge portions, said raw edge portions in opposed relation with each other and positioned at substantially the middle portion of each of said strips of conventional bias tape, said raw edge portions in direct contact with each other intermediate opposite sides of said first mentioned cloth strip.

5. The herein described method of preparing cloth material consisting in preparing several cloth strips, each of two pieces of conventional bias tape, then placing said cloth strips in parallel edge to edge adjacent relation with each other, then stitching said cloth strips together at their opposite ends, then stitching secondary cloth strips together in parallel edge to edge relation at one end, then interweaving said secondary cloth strips with said first mentioned cloth strips and then stitching said secondary cloth strips together at their opposite ends.

6. In a cloth material of the class described, the combination of interwoven cloth strips, each of said cloth strips constructed of two flat strips of conventional bias tape sewed together near opposite edges thereof.

EVELYN PASSAVANT.
